UNITED STATES PATENT OFFICE.

CHARLES DAY, GEORGE EDWARD WINDELER, AND PETER GRANT, OF HAZEL GROVE,
NEAR STOCKPORT, ENGLAND, ASSIGNEES TO GENERAL ELECTRIC COMPANY, A
CORPORATION OF NEW YORK.

INTERNAL-COMBUSTION ENGINE.

1,221,697.

Specification of Letters Patent.

Patented Apr. 3, 1917.

Application filed March 16, 1916. Serial No. 84,709.

To all whom it may concern:

Be it known that we, CHARLES DAY, GEORGE EDWARD WINDELER, and PETER GRANT, subjects of the King of Great Britain, and residents of Hazel Grove, near Stockport, county of Chester, England, have invented certain new and useful Improvements in Internal-Combustion Engines, of which the following is a specification.

10 The present invention relates to internal combustion engines in which liquid fuel is forced into the cylinder or cylinders by compressed air furnished by a suitable air compressor. In the operation of such engines it is desirable that the pressure of the air furnished by the compressor shall vary with the load on the engine; *i. e.*, increase as the load increases and vice versa.

15 The object of the present invention is to provide an improved arrangement for this purpose which will automatically vary the pressure in accordance with the load.

20 For a consideration of what we believe to be novel and our invention, attention is directed to the accompanying specification and the claims appended thereto.

25 In the accompanying drawing Figure 1 is a sectional view of a diagrammatic nature illustrating an embodiment of our invention, and Fig. 2 is a detailed sectional view of a modification.

30 Referring to the drawing, 9 indicates a portion of the casing of an air compressor and 10 its inlet, said compressor being used to supply compressed air for injecting fuel into an internal combustion engine. 11 is a valve casing which is connected to the inlet 10 by a conduit 12 fastened to the inlet by bolts 13. Inside the valve casing are two concentric valves 14 and 15. The outer valve 14 has an opening 16 which is adapted to register with the conduit 12 and the inner valve 15 has an opening 17 which is adapted to be brought into and out of alignment with the opening 16. The valve 14 is provided with a stem 18 which projects through the valve casing 11 and is connected to a movable abutment 19 which slides in a cylinder 20, which cylinder is preferably formed integral with the valve casing. 21 is a spring which is arranged between the movable abutment 19 and the valve casing and which

tends to bias the valve 14 to a position where its opening 16 is in alignment with the conduit 12. The lower end of the cylinder 20 is connected by a conduit 22 to the delivery conduit of the compressor or to the receiver containing a compressed air supply for the engine. The movable abutment 19, therefore, on the side opposite to the spring 21 is subjected to the pressure of the air delivered by the compressor. 23 indicates a portion of an internal combustion engine and 24 its governor which may be of any suitable type. The valve 15 is connected to the governor by stem 25 and lever 26 which is pivoted at 27 on a fixed support 28. One end of this lever is in engagement with the stem 25, while the other engages the sliding sleeve 29 of the governor. The valve 15 is provided with openings 30 through which air is admitted to the valve casing from which it flows to the compressor.

35 The operation is as follows: Assume that the engine is working and the valves 14 and 15 are in the position shown in Fig. 1. Air to the compressor enters by way of openings 30 to the interior of the valve casing and thence by way of openings 17 and 16 to the conduit 12 and into the compressor. If, now, the compressor for any reason fails to fully maintain the desired pressure, the movable abutment 19 will be forced downward by the spring 21. This will lower the valve 14 and bring the opening 16 to a position where it overlaps further the opening 17 thereby admitting more air to the compressor and preventing further drop in pressure. On the other hand, should the pressure in the receiver rise the piston 19 would be forced up and the air opening to the compressor reduced, with the result that less air will pass to the compressor and further rise of pressure prevented.

40 Should the load on the engine increase the engine speed will fall and the governor drop a little. This will raise the valve 15, bringing the port 17 more fully into alignment with port 16, thereby admitting more air to the compressor. On the other hand, should the speed of the engine increase, indicating a falling off in the load, the reverse action will take place, the valve 15 being lowered and diminishing the supply of air

- to the compressor. By this arrangement it will be seen that the pressure of the air delivered by the compressor and that in the receiver is varied in accordance with the 5 actual load on the engine and irrespective of variations in the efficiency of the air compressor, it being only necessary that the air compressor is of such size as to be capable of supplying sufficient air.
- 10 The ports 16 and 17 are so arranged relatively to each other and to the opening 12 that when the pressure on the delivery side of the compressor, or in the receiver, reaches a predetermined high value, the piston 19 is forced up to such an extent as to bring the opening 16 entirely out of registry with the conduit 12. This, then, completely cuts off the supply of air to the compressor. In Fig. 1 of the drawing the valve 14 is shown 15 as having almost reached the point where the supply of air to the compressor is completely shut off.
- 15 Various arrangements for connecting the valve mechanism to the governor and of the pressure responsive device may be used. For example, in Fig. 2 we have shown a modified form of movable abutment which 20 comprises a corrugated diaphragm 32 arranged in a casing 33. 34 is a compressed air conduit corresponding to conduit 22 of Fig. 1, and 35 is the outer valve member corresponding to the valve 14 of Fig. 1. The 25 operation of the arrangement shown in Fig. 2 is the same as that already described.
- 20 In accordance with provisions of the patent statutes, we have described the principle 30 of operation of our invention, together with the apparatus which we now consider to represent the best embodiment thereof; but we 35 desire to have it understood that the apparatus shown is only illustrative and that the invention can be carried out by other 40 means.

What we claim as new and desire to secure by Letters Patent of the United States, is:

1. The combination with an internal combustion engine and a compressor for supplying air thereto for injecting fuel into it, of 45 a plurality of valves for controlling the admission of air to the inlet of the compressor, means responsive to the load on the engine for positioning one of said valves, and means responsive to pressure of the air delivered 50 by the compressor for positioning another of said valves.

2. The combination with an internal combustion engine and a compressor for supplying air thereto for injecting fuel into it, of 55 a valve casing associated with the admission end of the compressor and having two valves therein which mutually control the admission of air to the compressor, means responsive to the load on the engine 60 for positioning one of said valves, and means

responsive to the pressure of the air delivered by the compressor for positioning another of said valves.

3. The combination with an internal combustion engine and a compressor for supplying air thereto for injecting fuel into it, of 65 a plurality of valves for controlling the admission of air to the inlet of the compressor, means responsive to the load on the engine for positioning one of said valves, and means 70 responsive to the pressure of the air delivered by the compressor for positioning another of said valves, said last named valve being arranged to completely cut off the admission of air to the compressor when the 75 pressure exceeds a predetermined value.

4. The combination with an internal combustion engine and a compressor for supplying air thereto for injecting fuel into it, of 80 a valve casing connected to the inlet of the compressor and having an opening communicating therewith, two valves in the casing which slide one within the other and have openings which are arranged to register with each other and with the opening 85 in the valve casing, and means connected with the valves and responsive respectively to the load on the engine and to the pressure of the air delivered by the compressor for positioning said valves to bring the openings 90 in them into and out of alinement.

5. The combination with an internal combustion engine and a compressor for supplying air thereto for injecting fuel into it, of 95 a valve casing connected to the inlet of the compressor and having an opening communicating therewith, two valves in the casing which slide one within the other and have openings which are arranged to register with each other and with the opening 100 in the valve casing, means connected with one of said valves for positioning it in accordance with the load on the engine, and means connected with the other for positioning it in accordance with the pressure of the air 105 delivered by the compressor, said last named means being adapted to position the valve to completely cut off the admission of air to the compressor when the pressure exceeds 110 a predetermined value.

6. The combination with an internal combustion engine and a compressor for supplying air thereto for injecting fuel into it, of 115 a valve mechanism for controlling the admission of air to the inlet of the compressor, a speed governor connected to the valve mechanism, and a pressure device responsive to the delivery pressure of the compressor also connected thereto, said governor and 120 device acting on the valve mechanism to 125 position it to regulate the admission of air to the compressor in accordance with the load on the engine.

7. The combination with an internal combustion engine and a compressor for supply- 130

ing air thereto for injecting fuel into it, of a valve casing connected to the inlet of the compressor and having an opening communicating therewith, two valves in the casing which slide one within the other and have openings which are arranged to register with each other and with the opening in the valve casing, a speed governor connected to one of said valves, a movable abut-

ment connected to the other, and a conduit 10 for conveying the pressure delivered by the compressor to the movable abutment.

In witness whereof, we have hereunto set our hands this 1st day of March 1916.

CHARLES DAY.

GEORGE EDWARD WINDELER.

PETER GRANT.
